AUTOMATIC WATER UNLOADER

William M. Lansdale and Conrad R. Buchet,
Los Angeles, Calif.

Application March 10, 1948, Serial No. 14,044

6 Claims. (Cl. 230—1)

1

This invention relates to means for ridding air compressors of accumulations of water and contemplates employing built-up pressure in the compressor for automatically accomplishing the same.

Electrically operated air compressors, conventionally, comprise an air compressing unit that is driven by an electric motor to store compressed air in a tank from which said air is drawn as needed. When the pressure in the tank falls below a predetermined low pressure point, the motor starts up to operate the compressor unit to raise the pressure in the tank. The motor, then, automatically stops when the pressure in the tank reaches a predetermined high pressure point. During operation, air pressure is built up in both the tank and in the compressor unit. The latter, therefore, offers high torque resistance to the electric motor when it seeks to start up. Accordingly, a pressure unloader is typically provided for the compressor unit so that the same is, in effect, vented. This relief of pressure in the compressor unit enables the motor to start up without undue load. Once started, the motor is capable of efficiently operating the compressor unit.

Heretofore, this pressure that is relieved from the compressor unit is released to atmosphere. According to this invention, and it is an object thereof, this otherwise wasted compressed air is utilized for the purpose of ridding the tank of such water that results when air is compressed.

Another object of the invention is to provide a novel water unloader that is connected to a compressed air tank and is operated by the pressure unloader of a compressor unit for said tank.

A further object of the invention is to provide such a water unloader that embodies adjustable means for controlling the time duration of its operation.

Our invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views.

2

Fig. 1 is a side elevational view of a conventional air compressor that embodies the water unloader of the present invention.

Fig. 2 is an enlarged longitudinal sectional view of the water unloader unit in which is embodied adjustable means for controlling the duration of operation.

Fig. 3 is a fragmentary view of said unit showing unadjustable clearance controlling the duration of operation.

With more particular reference to Fig. 1, the air compressor shown comprises an air tank 5 into which is directed compressed air by a compressor unit 6 that is driven by an electric motor 7. Conventionally, the compressor unit 6 is provided with a pressure unloader 8 for the reasons above stated. The foregoing conventional compressor is provided with a water unloader 9 and the same is connected by a tube 10 to the pressure unloader, so that pressure relieved from the compressor unit 6 operates the unloader 9.

Fig. 2 shows said unloader in detail and the same comprises, generally, a body 11, a fitting 12 for connecting the body to a nipple 13 (Fig. 1) that extends downward from the bottom of the tank 5, a valve 14 within the body and controlling flow from said tank, a piston 15 connected to the valve and in the path of flow of compressed air in tube 10 for operating said valve to release flow from the tank through an outlet 16, means 17 for restoring the valve to closed position automatically upon release of air pressure on the piston, and adjustable means 18 for metering the release of said air pressure to thereby control the time during which the valve is open.

The body 11 comprises a tubular part 19 that has an axial passageway 20. The tube 10, by means of a nut 21, is connected to the body part 19 so that air pressure will enter through passage 20 and into the chamber 22 thereof. Body part 19, near the end opposed to passage 20, has a threaded seat 23 for the outlet 16. Said latter end of the body is provided with internal threads for connection with an adapter part 24 that comprises part of the body 11. Said adapter part has a threaded extension 25 for connection to fitting 12.

An axial bore 26 is formed in part 24 and across said bore or in any suitable manner, there is provided a screen 27. Said screen is in the path of flow of water from tank 10 and serves to prevent scale and other foreign matter from entering bore 26.

The valve 14 comprises a bushing 28 that is fitted into bore 26, said bushing having an axial,

preferably round passage 29. The end of said bushing that is directed toward fitting 12 is formed to have a transverse valve seat 30. The seating part of the valve 14 comprises a compressible valve disc 31 that has flat engagement with valve seat 30 and a metallic retainer 32 for said disc.

A polygonal valve stem 33, in this case square, extends through bore 29 and has a cylindrical threaded extension 34 for mounting the valve disc 31 and retainer 32. A nut 35 serves to lock the latter in place on the stem 33.

The piston 15 is considerably larger in diameter than retainer 32 and the same is mounted on a reduced extension 36 of stem 33 and locked in place by a nut 37. The housing part 19 is machined with a smooth cylinder wall 38 and said piston is machined to operate therein with clearance 38a, as shown in Fig. 3, sufficient to permit a slow flow of compressed air from chamber 22 into and out of outlet 16.

The means 17 is shown as a coiled compression spring about stem 33 and arranged between bushing 28 and piston 15, the spring acting to urge the piston in a direction to cause valve 14 to close.

From the foregoing construction it will be seen that when the compressor unit 6 automatically unloads its pressure, this pressure is directed by tube 10 to enter chamber 22 and act against the face of piston 15. The latter is forced back against the pressure of spring 17 and valve 14 opens so that any water there may be in the bottom of tank 5, under the pressure in said tank, is blown out past valve 14, through passage 29, out through fitting 15 and a tube 39 on the outlet side thereof. Since the piston is fitted with some clearance as stated, the unloading pressure passes between the piston and wall 38 to become dissipated in a matter of a few seconds so that spring 17 is then enabled to close valve 14 and close tank 15 against further discharge therefrom.

As shown in Fig. 2, a variation of the above may be provided for effecting control of the time that the valve 14 remains open. The piston 15 is fitted more closely to have only sliding clearance with wall 38 or, even a sealing ring may be provided to obviate leakage around the piston. The adjustable means 18 is then provided to control the rate at which the unloading pressure dissipates. Means 18 is shown as a metering pin 40 that is threadedly extended through the wall of housing part 19, is locked in adjusted position by a nut 41, and has a tapered end 42 that fits into an opening 43 in the piston. The cylindrical part of pin 40 effectively closes said opening, but when the piston is forced back by unloading pressure, said opening becomes aligned with the tapered end 42 to provide an annular port for bleeding said pressure. Consequently, the size of said port depends on the adjusted position of means 18 and controls the duration that valve 14 is open. In the instance where little water is formed in tank 5, pin 40 is retracted for a rapid dissipation of the unloading pressure, and where much water is formed, a forwardly adjusted position of pin 40 causes a longer open time for valve 14.

While we have illustrated and described what we now regard as the preferred embodiment of our invention, the construction is, of course, subject to modifications without departing from the spirit and scope of our invention. We, therefore, do not wish to restrict ourselves to the particular form of construction illustrated and described,

but desire to avail ourselves of all modifications that may fall within the scope of the appended claims.

Having thus described our invention, what we claim and desire to secure by Letters Patent is:

1. A water unloader for compressed air tanks comprising a body connected to the bottom of said tank and having a passage for flow therefrom, a normally closed valve controlling said passage, a piston connected to the valve, and means for conducting fluid under pressure to act on said piston and open the valve, said body having a cylinder bore in which said piston is fitted with sufficient looseness to permit leakage of pressure around the piston whereby said pressure is rapidly dissipated and the valve is thereby opened momentarily.

2. A water unloader for compressed air tanks comprising, in combination, a body connected to the bottom of said tank and having a passage for flow therefrom, a normally closed valve controlling said passage, pressure responsive means within the body and connected to the valve to open the same momentarily, and means adjustably carried by the body and controlled from the outside thereof, said latter means having adjustable metering engagement with the pressure responsive means to control pressure flow past the latter means for controlling the time that the valve is open.

3. A water unloader for compressed air tanks comprising a body connected to the bottom of said tank and having a passage for flow therefrom, a normally closed valve controlling said passage, a piston connected to the valve, means for conducting fluid under pressure to act on said piston and open the valve, said piston having an opening therein, and adjustable means extending into said opening for controlling pressure flow therethrough and thereby the time that said valve is open.

4. A water unloader for compressed air tanks comprising a body connected to the bottom of said tank and having a passage for flow therefrom, a normally closed valve controlling said passage, a piston connected to the valve, means for conducting fluid under pressure to act on said piston and open the valve, said piston having an opening therein, and adjustable means extending into said opening for controlling pressure flow therethrough and thereby the time that said valve is open, said means comprising a tapered metering pin that varies the effective size of the port formed by said pin and the opening into which it extends.

5. An automatic water unloader comprising a hollow body having a cylindrical passage therein, a polygonal stem in said passage, a valve on one end of the stem, a piston on the other end, a spring for urging said piston and valve in one direction to close the passage to flow, and means for conducting fluid under pressure to act on said piston in a direction to open said valve against the force of said spring, said piston being so loosely fitted in the body that said fluid pressure is rapidly dissipated, whereby the spring becomes automatically effective to close the valve.

6. An automatic water unloader comprising a hollow body having a cylindrical passage therein, a polygonal stem in said passage, a valve on one end of the stem, a piston on the other end, a spring for urging said piston and valve in one direction to close the passage to flow, means for conducting fluid under pressure to act on said piston in a direction to open said valve against

the force of said spring, said piston being so loosely fitted in the body that said fluid pressure is rapidly dissipated, whereby the spring becomes automatically effective to close the valve, and adjustable means for controlling the rate of dissipation of the fluid pressure to control the time that said valve is open.
